UNITED STATES PATENT OFFICE.

CHARLES B. WHITNEY, OF HYDE PARK, MASSACHUSETTS, ASSIGNOR TO THE SIMPLEX FAUCET COMPANY, A CORPORATION OF MASSACHUSETTS.

FAUCET.

No. 902,786.

Specification of Letters Patent.

Patented Nov. 3, 1908.

Application filed May 12, 1906. Serial No. 316,509.

To all whom it may concern:

Be it known that I, CHARLES B. WHITNEY, a citizen of the United States, residing at Hyde Park, in the county of Norfolk and 5 State of Massachusetts, have invented new and useful Improvements in Faucets, of which the following is a specification.

This invention relates to improvements in faucets and ball cocks, the object of the invention being to provide a faucet or ball cock which is closed by the pressure of the water and in such a manner as to do away with the shock or jarring known as "water hammer."

The object is further to provide a device of the character referred to in which the valve is closed in such a manner that it will be sure to find its own seat thus preventing any tendency to leak, the valve being provided with a stem which extends longitudinally 20 upon opposite sides of the valve disk and is operated by certain means or mechanism hereinafter fully described which means or mechanism bears against the opposite ends of said stem, the valve thus being suspended 25 as it were between two points and only guided in its longitudinal movement from extreme lateral displacement.

The object of the invention is still further to so connect the lever by which the faucet 30 is opened that the casing may be swiveled relatively thereto to any desired position according to the location of the faucet or according to the desire of the person operating the faucet.

35 The invention consists in the combination and arrangement of parts set forth in the following specification and particularly pointed out in the claims thereof.

Referring to the drawings: Figure 1 is a central longitudinal section, partly in elevation, of a faucet embodying my invention. Fig. 2 is a section, partly in plan, taken on line 2—2 Fig. 1. Fig. 3 is an enlarged central longitudinal section partly in elevation of the plunger. Fig. 3^a is an enlarged side elevation of a modified form of plunger. Fig. 4 is an enlarged section of the disk and its locking nut attached to the valve stem, said valve stem being shown in elevation. Fig. 5 is a longitudinal section, partly in elevation, illustrating my invention applied to a ball cock for a closet tank, the ball cock lever being broken to save space.

Like numerals refer to like parts throughout the several views of the drawings.

In the drawings, referring to Figs. 1 to 4, inclusive, 8 is the casing of a faucet consisting of a body portion 9 having a spout 10, a base 11, and a cap 36. The base 11 is adapted to be fastened to a bowl and is formed in 60 the usual manner having a tubular shank 13 which projects through the fixture to which the faucet is to be attached and has a flange 14 at its end, said shank being screw-threaded at its lower end in order that it may be 65 clamped by suitable nuts to the fixture to which it is attached. The base 11 is attached by screw-threaded engagement therewith to the body portion 8 and has in the interior thereof an inlet passage 15 into which an annular flange 16 projects. The body portion 9 is also provided with an annular flange which forms a seat 17 for the valve 18. The valve 18 consists of a stem 19 which has attached thereto a disk 20 provided with a 75 washer 21 located in a cylindrical recess formed in the upper face of said disk.

The disk 20 has screw-threaded engagement with the stem 19 and bears upon its upper face against a flange 22 integral with the stem 19, said disk is pressed against the flange 22 and held locked upon the stem 19 by means of a nut 23. The lower end of the stem 19 bears against the top of a plunger 24 adapted to slide longitudinally thereof in the 80 inlet passage 15. Said plunger is preferably constructed of a tube 25 closed at its lower end as seen in Fig. 3, and provided with slots 26 extending longitudinally thereof. The upper end of the tube 25 has an inverted 85 cup-shaped head 27 provided with perforations 28.

In its operation the head of the plunger 24 has sliding contact with the walls of the inlet passage 15 and the tubular shank 25 95 slides in contact with the annular flange 16. A spiral spring 29 encircles the tubular shank 25, one end bearing against the head 27 and the other end thereof bearing against the annular flange 16. The valve 18 is moved 100 away from its seat by means of a lever 30 and pin 31. The pin 31 has an annular flange 32 thereon, which slides in a cylindrical recess 33 formed in the top of the body portion 9 of the casing. The upper end of 105 the pin 31 bears against the underside of the lever 30, said lever being provided with a pivot 34 which extends laterally therethrough and into a holder 35, which is enclosed within the cap 36.

The holder 35 is slotted at 37 and the cap 36 is slotted at 38 to receive the lever 30 and to allow said lever to rock upon its pivot. The cap 36 has an annular flange 39 upon the bottom thereof which projects beneath a similar flange 40 formed upon a sleeve 41 which has screw-threaded engagement with the top of the body portion 9 of the casing. The sleeve 41 at its lower edge bears against the shoulder 42 formed upon the body portion 9, said shoulder being so located that when the sleeve 41 is screwed down firmly thereagainst the cap 36 will be held against the top of the body portion of the casing, but will be free to rotate thereon, so that the lever 30 can be rotated with said cap and with the holder 35 to any desired position relatively to the casing, thus adapting the lever to be placed in different positions as may suit the convenience of the user or as may suit the requirements of the faucet when placed in different positions.

The stem 19 is preferably rounded at the top and bottom thereof so that it bears against the lower end of the pin 31 and against the upper end of the plunger 24 upon a very small area. The disk 20 is guided against any extended lateral displacement by guide ribs 42 integral with the casing body 9 and projecting inwardly from said casing toward the center of the stem 19. There is, however, a slight space between the periphery of the disk 20 and these ribs 42 which allows the valve to move freely and also allows the disk to seek its own seat upon the valve seat 17, thus preventing any leakage.

In Fig. 1 the lever 30 is shown depressed, the valve being opened and the flange 32 upon the pin 31 pressing against the bottom of the recess 33, this flange thus prevents any leakage around the lever 30 and cap 36 due to back pressure of the water when the valve is opened. The interior of the body portion of the casing above the valve seat 17 constitutes an outlet chamber 43, the interior of the body portion of said valve below the valve seat constitutes an inlet chamber 44, into which the inlet passage 15 opens.

The slots 26 in the tube 25 are so located that when the valve is closed said slots terminate above the lower edge of the annular flange 16, and when the valve is open said slots project downwardly below said annular flange.

Having thus specifically described my invention, I will now proceed to describe the operation thereof having still reference to Figs. 1 to 4, inclusive. Assuming the valve to be open as illustrated in Fig. 1, the water will enter through the inlet passage 15 in the direction of the arrow *a*, Fig. 1, and will pass through the slots 26 into the interior of the plunger 25 and completely fill the inlet passage 15. Pressing the flange 27 upwardly against the bottom end of the stem 19, the

water will flow through the perforations 28 and into the inlet chamber 44, from this it will pass through the space between the valve disk and valve seat into the outlet chamber 43 thence flowing outward through the spout 10. Upon releasing the lever 30 the pressure of the water will close the valve by pressing upwardly upon the plunger until the disk 20 comes to a seat upon the valve seat 17. During the latter portion of the upward movement of the plunger, the slots 26 move upwardly until the bottoms of said slots are located above the bottom of the annular flange 16 and the water is thus gradually shut off from direct connection with the valve, but will still press against the bottom of the plunger and hold the same firmly against the lower end of the stem of the valve, whereby said valve is kept against the seat.

The function performed by the spring 29 is to assist the operation of the device in preventing a rebound or jarring of the valve after it has come to a bearing upon its seat, but the gradual shutting off of the water by the slotted plunger 26 is the principal cause in this device of the elimination of such jarring or hammering known as the "water hammer".

It will be understood that the plunger 24 is preferably a differential plunger, that is, the area of the head minus the area of the perforations therein is greater than the area of the lower end of the shank, so that when the valve is open as in Fig. 1 and the pressure upon the lever 30 is removed, the force of the water tending to close the valve in so far as the upward pressure upon the under side of the head is concerned, is greater than the pressure of the water downwardly upon said plunger against the upper or inner face of the bottom thereof, but not so great as would be the case if the plunger were not a differential plunger. In other words, the area of the under side of the head 27 minus the area of the perforations therein and minus the area of the upper face of the bottom of the plunger 24 is greater than the area of the lower face of the bottom of said plunger. Therefore, the pressure on the lower face of the plunger 24 plus the pressure on the under side of the head 27 is greater than the pressure on the upper side of the lower end of said plunger. Consequently, the plunger 24 moves upwardly assisted by the spring 29, but the lower ends of the slot 26 almost immediately pass beyond the bottom of the annular flange 16, thereby shutting off the supply of water from the inlet passage 15 to the passages above the annular flange 16. Pressure now exists only on the lower face of the lower end of the plunger 24. The pressure on the lower face of the bottom of the plunger 24 assisted by the spring 29 still continues to move the plunger upwardly, but water, of

course, remains in the inlet chamber 44 and in the outlet chamber 43. As the plunger 24 continues to move upwardly, the space between the head 27 and the flange 16 increases and, therefore, continued upward movement of the plunger 24 tends to produce a vacuum in the space between said head and said flange and, therefore, a portion of the water contained in the chamber 44 is compelled to flow downwardly through the perforations 28 and outwardly through the slots 26 into the space surrounding the tube 25. This tendency to form a vacuum between the head 27 and the annular flange 16 obviously checks the upward movement of the plunger 24 and its speed is limited by the speed of the water which flows downwardly through the perforations 28 through the slots 26 and into the space between the head 27 and flange 16. Therefore, after the lower ends of the slots 26 have passed upwardly beyond the under side of the flange 16, the upward movement of the plunger 24 and disk 20 is very slow and said disk is moved into contact with its seat 17 very gently without rebound or hammering. If desired, the plunger may be made with the slots 26' of different lengths or with their lower ends terminating at different distances from the bottom of the plunger as illustrated in Fig. 3^a.

In Fig. 5 I have illustrated a modified form of my invention adapted to be used as a ball cock in which the principle of operation is the same as that described in Figs. 1 to 4, inclusive, except that the lever 30 of the form hereinbefore described is replaced by a lever 30' which is a ball cock lever and is supported upon a pivot 34' fast to ears 45 formed upon the casing 8'. The lever 30' has a cam-shaped or eccentric-shaped disk 46 integral therewith which bears against one end of the pin 31'. The casing 8' consists of a body portion 9' having a spout 10' and a base 11'. The valve 18' consists of a stem 19' and a disk 20' which is adapted to bear against the seat 17' formed in the casing. The plunger 24' bears against one end of the valve stem 19' and is encircled by a spring 29'. The action of this device is exactly similar to the action of the form of my invention which I have described and illustrated in Figs. 1 to 4, inclusive, in so far as the operation of the pin 31', valve 18', and plunger 24' is concerned.

Having thus described my invention what I claim and desire by Letters Patent to secure is:

1. A faucet comprising in its construction a casing provided with an inlet chamber and an outlet chamber, there being an inlet passage connecting with said inlet chamber, a valve seat located in said casing between said inlet and outlet chambers, a valve adapted to be pressed against said seat by the pressure of the water, and a hollow differ-

ential plunger adapted to slide in said inlet passage and bearing against said valve, said plunger having sliding contact with the walls of said inlet passage.

2. A faucet comprising in its construction 70 a casing provided with an inlet chamber and an outlet chamber, there being an inlet passage connecting with said inlet chamber, a valve seat located in said casing between said inlet and outlet chambers, a valve adapted 75 to be pressed against said seat by the pressure of the water, and a hollow differential plunger adapted to slide in said inlet passage and bearing against said valve, said plunger having sliding contact with the walls of said 80 inlet passage, and being provided with slots in its periphery extending longitudinally thereof for a portion of its length and with holes in the end thereof adjacent to said valve.

3. A faucet comprising in its construction a casing provided with an inlet chamber and an outlet chamber, there being an inlet passage connecting with said inlet chamber, a valve seat located in said casing between said 90 inlet and outlet chambers, a valve adapted to be pressed against said seat by the pressure of the water, a plunger adapted to slide in said inlet passage consisting of a perforated head, and a hollow slotted shank, the area of 95 said head minus the area of said perforations therein being greater than the area of the end of said shank farthest removed from said head, said head adapted to slide in contact with the interior wall of said inlet passage, 100 and said shank adapted to slide in contact with an annular flange in said inlet passage, the slots in said shank being so located that when said valve is in contact with said seat 105 said slots are located between said annular flange and valve seat.

4. A faucet comprising in its construction a casing provided with an inlet chamber and an outlet chamber, there being an inlet passage connecting with said inlet chamber, a valve seat located in said casing between said 110 inlet and outlet chambers, a valve adapted to be pressed against said seat by the pressure of the water, a plunger adapted to slide in said inlet passage consisting of a perforated 115 head and a hollow slotted shank, the area of said head minus the area of said perforations therein being greater than the area of the end of said shank farthest removed from said head, said head adapted to slide in contact 120 with the interior wall of said inlet passage and said shank adapted to slide in contact with an annular flange in said inlet passage, the slots in said shank being so located that when said valve is in contact with said seat, 125 said slots are located between said annular flange and valve seat, and a spring encircling said shank, one end bearing against said head, the other against said flange.

5. A faucet comprising in its construction 130

- 5 a casing provided with an inlet chamber and an outlet chamber, there being an inlet passage connecting with said inlet chamber, a valve seat located in said casing between said inlet and outlet chambers, a valve consisting of a disk and a stem fast thereto and projecting beyond said disk upon opposite sides thereof, said disk adapted to be pressed against said seat by the pressure of the water, a differential plunger adapted to slide in said inlet passage and bearing against one end of said stem and means bearing against the opposite end of said stem to force said disk away from said valve seat.
- 10 6. A faucet comprising in its construction, a casing provided with an inlet chamber and an outlet chamber, there being an inlet passage connecting with said inlet chamber, a valve seat located in said casing between said inlet and outlet chambers, a valve consisting of a disk and a stem fast thereto and projecting beyond said disk upon opposite sides thereof, said disk adapted to be pressed against said seat by the pressure of the water, a differential plunger consisting of a head and a shank of smaller diameter than said head, said head bearing against one end of said stem and adapted to slide in contact with the interior wall of said inlet passage, a 25 slideable pin bearing against the opposite end of said stem, and a lever pivoted to said casing and bearing against said pin.
- 20 7. A faucet comprising in its construction a casing provided with an inlet chamber and an outlet chamber, there being an inlet passage connecting with said inlet chamber, a valve seat located in said casing between said inlet and outlet chambers, a valve adapted to be held against said seat by the pressure of the water, a differential plunger consisting of a head and a shank of smaller diameter than said head, said head bearing against said valve, a pin slideable in a recess provided in said casing one end thereof bearing against 25 said valve, an annular flange on said pin, and means to move said pin longitudinally of said valve, whereby said valve is moved away from said seat and said flange is brought into contact with the bottom of said recess.
- 30 8. A faucet comprising in its construction a casing provided with an inlet chamber and an outlet chamber, there being an inlet passage connecting with said inlet chamber, a valve seat located in said casing between said inlet and outlet chambers, a valve adapted to be pressed against said seat by the pressure of the water, a differential plunger consisting of a head and a shank of smaller diameter than said head, said head bearing against said valve, said head being provided with ports extending therethrough, a pin slideable in a recess provided in said casing one end thereof bearing against said valve, an annular flange on said pin, means to move said
- 35 pin longitudinally of said valve, whereby 65 said valve is moved away from said seat and said flange is brought into contact with the bottom of said recess, a holder adapted to rotate about a vertical axis, and a lever adapted to rock upon said holder about a horizontal axis, said lever adapted to bear against said pin.
- 40 9. A faucet comprising in its construction a casing provided with an inlet chamber and an outlet chamber, there being an inlet passage connecting with said inlet chamber, a valve seat located in said casing between said inlet and outlet chambers, a valve adapted to be pressed against said seat by the pressure of the water, a differential plunger having a head adapted to slide in said inlet passage and bearing against one side of said valve, said head having ports extending therethrough, and means bearing against the opposite side of said valve adapted to force 85 said valve away from said valve seat.
- 45 10. A faucet comprising in its construction a casing provided with an inlet chamber and an outlet chamber, there being an inlet passage connecting with said inlet chamber, a valve seat located in said casing between said inlet and outlet chambers, a valve adapted to be pressed against said seat by the pressure of the water, a differential plunger consisting of a head and a shank of smaller diameter than said head, said head bearing against said valve and adapted to slide in contact with the interior wall of said inlet passage and said shank adapted to slide in contact with an annular flange in said inlet 50 passage, said plunger having passages extending longitudinally thereof, said second passages adapted to communicate from said first passage to said inlet chamber when said valve is moved from said seat, and a spring 10 encircling said shank, one end bearing against said head and the other against said flange.
- 55 11. A faucet comprising in its construction a casing provided with an inlet chamber and an outlet chamber, there being an inlet passage connecting with said inlet chamber, a valve seat located in said casing between said inlet and outlet chambers, a valve adapted to be held against said seat by the pressure 11 of the water, a differential plunger consisting of a head and a shank of smaller diameter than said head, said head bearing against said valve and adapted to slide in contact with the interior wall of said inlet passage 12 and said shank adapted to slide in contact with an annular flange in said inlet passage, a pin slideable in said casing, one end thereof bearing against said valve, a rotatable holder, a lever pivoted to said holder and adapted to bear against said pin, and a rotatable cap 12 enclosing said holder.
- 60 12. A faucet comprising in its construction

a casing provided with an inlet chamber and an outlet chamber, there being an inlet passage connecting with said inlet chamber, a valve seat located in said casing between said 5 inlet and outlet chambers, a valve adapted to be pressed against said seat by the pressure of the water, and a differential plunger consisting of a head and a shank of smaller diameter than said head, said head bearing 10 against said valve, said plunger having sliding contact with the walls of said inlet passage.

13. A faucet comprising in its construction a casing provided with an inlet chamber and an outlet chamber, there being an inlet passage connecting with said inlet chamber, a valve seat located in said casing between said inlet and outlet chambers, a valve adapted to be pressed against said seat by the pressure of the water, and a differential plunger 20 consisting of a head and a shank of smaller diameter than said head, said head bearing against said valve and adapted to slide in contact with the interior wall of said inlet 25 passage and said shank adapted to slide in contact with an annular flange in said inlet passage, said head provided with ports extending therethrough, the area of said head

being greater than the end of said shank farthest removed from said head. 30

14. A faucet comprising in its construction a casing provided with an inlet chamber and an outlet chamber, there being an inlet passage connecting with said inlet chamber, a valve seat located in said casing between said inlet and outlet chambers, a valve adapted to be pressed against said seat by the pressure of the water, and a differential plunger 35 consisting of a head and a shank of smaller diameter than said head, said head bearing 40 against said valve and adapted to slide in contact with the interior wall of said inlet passage, said shank adapted to slide in contact with an annular flange in said inlet 45 passage, said plunger being provided with passages extending longitudinally thereof adapted to communicate from said inlet passage to said inlet chamber when said valve is moved away from said seat.

In testimony whereof I have hereunto set 50 my hand in presence of two subscribing witnesses.

CHARLES B. WHITNEY.
